UNITED STATES PATENT OFFICE.

GUSTAVE OLSON, OF CHICAGO, ILLINOIS.

SALT AND PEPPER BOX.

Application filed April 21, 1924. Serial No. 707,989.

To all whom it may concern:

Be it known that I, GUSTAVE OLSON, a citizen of the United States, and a resident of the city of Chicago, county of Cook, and 5 State of Illinois, have invented certain new and useful Improvements in Salt and Pepper Boxes, of which the following is a specification:

My invention relates to improvements in 10 salt and pepper boxes, and has for its object the provision of an improved combination box of this character adapted and arranged to contain both salt and pepper and equipped with improved means whereby 15 either salt or pepper may be discharged from the box as desired.

Other objects will appear hereinafter.

The invention consists in the combinations and arrangements of parts hereinafter 20 described and claimed.

The invention will be best understood by reference to the accompanying drawings forming a part of this specification, and in which—

25 Fig. 1 is a side view of a box embodying the invention;

Fig. 2, a section taken on line 2—2 of Fig. 1;

Fig. 3, a top plan view of the box;

30 Fig. 4, a section taken on line 4—4 of Fig. 2;

Fig. 5, a partial section taken on line 5—5 of Fig. 3, and

35 Fig. 6, a section taken on line 6—6 of Fig. 4.

The preferred form of construction as illustrated in the drawings comprises a cylindrical receptacle 7 of the form indicated and having an open bottom. A removable 40 bottom member 8 is provided for said receptacle and a flange 9 is provided on said bottom to fit snugly within the lower portion of said receptacle. The flange 9 is provided with two oppositely arranged cam 45 tongues 10 cut from the body of the flange and bent inwardly as shown, the lower corners of the partition 11 being provided with notches 12 to receive the flange 9 and openings 13 to receive said cam tongues. As 50 will be noted the lower edges of the tongues 10 are downwardly inclined to form in effect screw cam surfaces engaging with the bottoms of the openings 13 to tighten the bottom 8 in place when the bottom 8 is rotated. 55 By this arrangement the bottom 8 may be readily inserted with the flange 9 fitting into

the notches 12 and upon rotation of the bottom member the tongues 10 will automatically engage the openings 13 and draw the bottom member 8 snugly into closing position.

The partition 11 is provided at its upper end with a central threaded stem 14 projecting through a central opening in the top 15 of the receptacle 7. A threaded nut or 65 knob 16 engages the stem 14, as shown, to lock the parts in place. A rotatable cap 17 is fitted over the top of receptacle 7 and provided with escape openings 18 adapted and arranged to register alternately with 70 corresponding escape openings 19 in the top of receptacle 7. The openings 19 are diametrically arranged and the openings 18 are angularly displaced as best shown in Fig. 3 and whereby when the cap 17 is shifted into 75 one position one set of openings are brought into registration and when the cap 17 is shifted into its other position the other set of openings are brought into registration, the first set being closed. The cap 17 is 80 provided with a handle lip 20 for convenience in shifting the same and a stop pin 21 is extended through the wall of receptacle 7 engaging a notch 22 in cap 17 to limit the movements of caps 17 with one or the other 85 set of openings 18—19 in registration with each other. The pin 21 also serves as a stop for the partition 11 to cause the same to extend transversely between the escape openings 19. By this arrangement salt may be 90 supplied to the receptacle 7 on one side of partition 11 and pepper on the other side and either may be discharged therefrom when desired by shifting the cap 17 to bring one or the other set of escape openings into 95 registration with each other.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of 100 the appended claims.

Having described my invention, what I claim as new and desire to secure by Letters Patent is:

1. A device of the class described comprising a cylindrical receptacle open at the bottom; a removable vertical partition fit-

ting said receptacle; a threaded stem on the top of said partition projecting through the top of said receptacle; a removable cap fitting over the top of said receptacle and 5 rotatable on said stem there being openings in said cap and corresponding openings in said top, the openings in said cap being angularly displaced with reference to the openings in said top but arranged to be 10 brought alternately into and out of registration therewith; a nut on said threaded stem holding said cap and partition in place; and a removable bottom for said receptacle, substantially as described.

2. A device of the class described comprising a cylindrical receptacle open at the bottom; a vertical partition fitting said receptacle; a threaded stem at the top of said partition projecting through the top of said receptacle; a cap fitting over the top of said receptacle there being openings in said cap and corresponding openings in said top, the openings in said cap being angularly displaced with reference to the openings in said 25 top but arranged to be brought alternately into and out of registration therewith; a nut on said threaded stem holding said cap and partition in place; a removable bottom for said receptacle having a flange fitting

snugly into the bottom thereof; and two 30 oppositely arranged cam tongues struck from said flange and bent inwardly, there being notches in the lower corners of said partition to receive said flange and inwardly spaced openings in said partition to receive 35 said tongues, substantially as described.

3. A device of the class described comprising a cylindrical receptacle open at the bottom; a vertical partition fitting said receptacle; a removable bottom for said receptacle having a flange fitting snugly into the bottom thereof; and two oppositely arranged cam tongues struck from said flange and bent inwardly, there being notches in 40 the lower corners of said partition to receive said flange and inwardly spaced openings in said partition to receive said tongues; and selective means at the top of said receptacle for discharging material from either side of said partition, substantially as described.

In testimony whereof I have signed my name to this specification in the presence of two subscribing witnesses.

GUSTAVE OLSON.
